HIGH-SPEED MILLING MACHINE

Theodore S. See, Hammond, Ind., assignor to La Salle Steel Company, Chicago, Ill., a corporation of Delaware

Application May 11, 1949, Serial No. 92,725

4 Claims. (Cl. 90—16)

1

This invention relates to machines for the removal of material from round, metal bar stock and more particularly to a milling machine for round bars adapted for efficient operation with cutter speeds substantially higher than those commercially employed today.

In my co-pending application Serial No. 7,372 filed February 10, 1948, there is disclosed a new and improved method of milling metal surfaces and a cutter adapted for use in the practice of the method. According to my new method accelerated operations, including cutter speeds and work feed rates, are obtained which are substantially faster than those now employed or now available. Present day machines are not built to operate at such vastly increased speeds. Accordingly the successful practice of the new method at such speeds involves the design and construction of machines having greatly increased spindle speeds for cutters, greatly increased feeding rates for the work pieces and, equally important, new and improved structural or machine arrangements adapted to accommodate such accelerated speeds and rates of feed.

In designing and constructing new machines of this character, the natural tendency is towards heavier, more complicated and therefore more expensive structures. However, an important object of the present invention resides in the provision of a novel machine of this character which, while comparatively simple in design and construction, is sufficiently rugged for successful operation at these muchly elevated speeds and is comparatively inexpensive to manufacture. Not only are commercial milling machines of today slow in operation and performance but current research teaches that the successful milling of metal surfaces should be performed at slow speeds and argues away from the employment of higher rates. Furthermore, when the literature does speak of high or higher milling speeds, it refers to rates of operation that are only reasonably increased beyond those employed today and does not contemplate the vastly increased speeds obtained and employed by the present novel technique.

Thus where spindle speeds have heretofore been experimentally stepped up increment by increment the present invention contemplates employing feed rates and surface foot rates that at the lowest are substantially above those being employed today. The machine which forms the subject matter of this application is primarily intended for operation at such increased speeds.

While the patented art sporadically refers to

2

high speeds and occasionally discloses an isolated attempt to perform some special cutting operation at an elevated swiftness, nothing in the prior art discloses the performance of standard or commercial milling operations at the speeds obtained or in the manner described in this and the co-pending application referred to above.

In accordance with the foregoing desideratum a feature of the present invention resides in the provision of a new and improved bar milling machine designed to operate at what may be termed super speeds without undue vibration. This feature is accomplished to a favorable extent by mounting the driving mechanism and the 15 housings for the cutters upon a common axis.

Another feature of the invention resides in the provision in a machine of this character of a cutter assembly and supporting parts which permits convenient replacement of cutters and 20 adapts the machine to operate successfully on work pieces and with cutters of different sizes.

Other objects and features of the invention will become apparent from a reading of the following specification in the light of the accompanying drawing, in which,

Figure 1 is a top plan view of a milling machine constructed in accordance with the present invention.

Figure 2 is a view in front elevation of the 30 machine shown in Figure 1.

Figure 3 is an enlarged view of the machine, also in front elevation, with certain parts broken away.

Figure 4 is a view in side elevation, partly in 35 section, of the machine of the earlier figures.

Figure 5 is a side elevational view, similar to Figure 4, showing the driving apparatus, and

Figures 6, 7, 8 and 9 are detail views of the 40 main frame, the housing for the driving mechanism, and a section of the work support.

As shown in Figure 1 of the drawings, the assembly comprises, in general, a plurality of cutters 10 and 12, mounted on oppositely extending shafts 14 and 16 which are driven at accelerated speeds by means of gear trains mounted in housing 18 and 20. Adjusting mechanisms 22 and 24 control the position of the cutters and may be employed in order to accommodate the machine to work pieces A of different size and 45 likewise to cutters having different diameters.

In order to feed the work piece A through the 50 milling machine a pair of rolls 26 and 28 are provided. These rolls may be constructed in accordance with the principles of the so-called

Medart machine disclosed in Patent No. 2,132,976.

A similar, cooperating pair of rolls 30 and 32 positioned at the opposite side of the machine are provided to feed the work away from the machine after it passes from the cutters 10 and 12.

Turning now to Figure 2, it will be seen that the machine may be conveniently mounted on a concrete floor B provided with pits C and D within which are positioned electric motors 34 and 36. These motors drive the cutters 10 and 12 at elevated speeds through acceleration gears mounted in the housings 18 and 20. A main frame 40 is secured to the floor or deck B in any suitable manner and supports the milling assembly.

As shown in Figure 3, the main frame 40 is provided with bearings 42, 44 and 46 which provide rotatable support for a plurality of stub or rocker shafts 48 and 50. The inner extremities of these shafts terminate near one another within the bearing 44 as illustrated. Cutter housings 52 and 54, as shown in Figures 3 and 4 are mounted on the stub shafts 48 and 50 respectively. These housings are yoke shaped at their upper extremities, the housing 52 being divided into a plurality of arms 56, 58 and the housing 54 into a plurality of arms 60, 62 (Figure 1). Each of these arms is bifurcated to provide slots for the reception of wedge-shaped members 64 depending from and supporting bearings 66 (Figure 4). Pins or keys 68 lock the bearings to the housing arms.

The oppositely extending cutter drive shafts 14 and 16 are mounted in the bearings 66 and at their outer extremities are mounted in the housings 18 and 20 by means of bearings 70 (Figure 3). The gear trains for each cutter shaft comprise a series of acceleration gears commencing with a gear 72 keyed to the shaft of the motor 34 or 36. This gear meshes with a smaller gear 74 rotatably journaled on the reduced extremity of the stub shafts 48 and 50. Additional gears 76 and 78, each smaller than its predecessor, are mounted in shafts formed integrally with the housings 18 and 20 and are provided for the purpose of driving gears 80 splined to the cutter shafts. These gear trains, driven initially by high speed motors cause the cutters to rotate at the high speeds contemplated by the invention as hereafter more fully explained.

The cutter housings are mounted for adjustment or movement towards or away from the axis X of the work piece in order that the milling operation may be performed on work pieces or with cutters of different diameters. To this end, each of the cutter housings 52 and 54 is provided with a yoke shaped member 82, 84 (Figures 1 and 4) pivoted thereto. Links 86, 88 connect the yokes with bolts 90 and 92 as clearly shown in Figure 4. These bolts have screw threaded connection with the hubs of hand-wheel members 94 and 96 journaled in the machine frame. Thus, rotation of the hand wheels causes the cutters to move inwardly or outwardly.

Referring to Figures 5, 7 and 8 it will be seen that the gear housings 18 and 20 are divided along the line 100 in such a manner that the upper portions of the housings are free to swing or pivot with the gears 76 and 78 about the stub shafts 48 and 50, thereby permitting adjustment of the cutter shafts 14 and 16 to take place without interference from the gears or the gear housings.

To facilitate removal of the cutters from the machine suitable shaft couplings 102, 104 are provided.

As illustrated, the machine is provided with apparatus for supporting the work piece as it moves

between the cutters and this apparatus is adjustable in order to accommodate work pieces of different sizes. Figures 1 and 2 show this apparatus generally while Figures 3, 4 and 5 show it in greater detail. A plurality of cross frame members 106 and 108 span the cutter assembly and are secured to the main frame 40. Centrally formed atop these cross frames are web portions 110, 112 each having a smooth, rectangular bore 114 formed therein.

A housing 116 is inserted within each rectangular bore 114 and is vertically adjustable by means illustrated in Figure 3. As there shown, bolt members 118 are formed integrally with and adapted to extend upwardly from the cross frames 106 and 108. Each housing 116 is provided with an integrally formed laterally projecting arm 120 having a cylindrical bore therein to receive a bolt member 118. Nuts 122, 124 are threaded on each of the arms 118 on either side of the arm 120 and by adjusting the bolts the height of the projecting arms 120 may be varied and controlled as desired. Set screws operated by hand wheels 128, 130 are provided to lock the arms in adjusted position.

Mounted within the lower, closed ends of the housings 116, as shown in Figure 4, are work supporting rolls 132. These rolls are journaled on pins carried by the housings and are freely rotatable. The position of these rolls with respect to the axis X of the work can be adjusted by raising or lowering the housings 116 to accommodate work pieces of different diameters.

Cooperating rolls 134 (also Figure 4) are rotatably mounted in a sleeve 136 pivotally attached, by means of a pin 140, to a rod or bar 142. The sleeve 136 and the rolls 134 are normally urged toward the bar axis by means of a compression spring 144 but are free to move momentarily away from this axis if such movement is called for in the feed of the bar through the machine. To this latter end, the bar 142 is slidably mounted within a sleeve 150, expanded as shown at 152 to provide an abutment for the spring 144, and having its upper end threaded for engagement with cooperating threads formed within the hub 154 of a rotary hand wheel 156. Rotation of the latter causes the sleeve 150 to rise or descend carrying with it, under compression of the spring 144, the rod 142, the sleeve 136 and the work rolls 134. In order to adjust the compression of the spring 144, a second hand wheel 160 having screw threaded engagement with the upper extremity of the rod 142 is provided.

Each of the assemblies made up of the housing 116, the sleeve 136 and the two sets of rolls 132 and 134, together with the attendant supporting and adjusting means, comprises a steady rest for the rotating bar stock as it passes lengthwise through the machine. As shown in Figures 1, 2 and 3 these steady rests are positioned on opposite sides of the cutters 10, 12, immediately adjacent thereto, in such a manner as to support the bar firmly as it enters and emerges from the bite of the cutter.

Figure 6 shows the frame of the machine and the manner in which the cutter housings 52, 54 are mounted on the rock shafts 48 and 50.

To facilitate removal of chips during a milling operation the machine is equipped with a suction chute 164. If the cutters are driven to rotate in the direction indicated by the arrows in Figure 4 the chips will have a tendency to fall

into the chute and be disposed of without difficulty.

In operation, round bar stock is fed to the machine in any suitable manner. The rolls of the so-called Medart machine can be regulated to control the speed of rotation of the round bars as they are milled.

In the Medart machine one roll is cylindrical and the other concave and by adjusting the angularity and the speed of rotation of the rolls, the linear rate of feed of the bars can be controlled and likewise the speed of rotation of the bars about their own axes may be regulated. As stated, a machine of this character is disclosed in Patent No. 2,132,976 granted to Siegerist on October 11, 1938.

Ordinarily a depth of cut of about $\frac{1}{2}$ of an inch will be taken and the diameter of the cutters will ordinarily vary from 4 to 12 inches. The cutter itself is preferably constructed in accordance with my co-pending application first above mentioned.

As already stated, it is intended that this machine should be capable of operation at speeds substantially above those now employed. Also it is contemplated that its use, in so far as materials are concerned, should be universal. Thus the machine may be employed to machine the surface of both ferrous and non-ferrous bar stock. Today special machines are generally constructed for each of these materials. Of them, steel and cast iron are the most difficult to machine and previously they have been handled at comparatively low speeds and feeds. For instance the top feed rate on steel has generally been about 90 I. P. M. (inches per minute) and the top surface foot rate of the cutter 1000 S. F. M. (surface feet per minute). In accordance with my invention the I. P. M. will preferably commence at 120 and go as high as 3,000 or even higher.

Similarly, the surface foot rate will be increased from a range of 250 (to an occasional 1,000) to a range of 1,500 to 20,000 or higher. The upper limits of my invention as set forth herein and in co-pending applications will generally depend on physical limitations of machine and cutter design only and the lower limits will lie substantially above those previously deemed feasible or possible. Particularly is this true of the ferrous field where I have discovered, contrary to popular belief, that the higher speeds and feeds the more facile the operation when my cutters and machine construction are employed.

Although in the machine illustrated in the accompanying drawings the work pieces (round metal bars) are fed past the cutters in a horizontal direction, it will be appreciated that a person skilled in the art could readily provide a vertically downward or upward feed for work pieces such as flats, squares, hexagons or the like or could, in the vertical mill, substitute form cutters for the cylindrical cutters for operation on special shapes and sections without departing from the scope of the invention as set forth in the appended claims. Similarly the cutter axes shown in the illustrated embodiment could be disposed vertically for a similar purpose although this would perhaps be less satisfactory from the standpoint of machine balance.

Other changes and modifications in construction and arrangement of parts will occur to those skilled in the art and may also be employed within the meaning of the following claims.

Having thus described the invention, what is claimed as new and for which protection is desired, is:

1. A machine for milling round metal bar stock, constructed and arranged for operation at a work piece feed rate of above 90 I. P. M. and a cutting speed of above 1500 S. F. M., said machine comprising, in combination, a pair of opposed rotary cutters, a rock shaft, cutter housings pivoted to said rock shaft and carrying said cutters, and independent means for varying and controlling the position of each of said cutters with respect to the other.
2. A machine for milling round metal bar stock at high speeds comprising a pair of substantially parallel cutter shafts, a pair of opposed rotary cutters respectively disposed on said cutter shafts, a rock shaft, cutter housings pivoted on said rock shaft and having bifurcated upper ends for supporting said cutter shafts at opposite ends of said cutters, and independent means for varying and controlling the position of each of said cutters with respect to the other.
3. A machine for milling round metal bar stock at high speeds comprising a frame, rock shaft means extending across said frame and projecting from opposite ends thereof, a pair of cutter shafts respectively projecting beyond the opposite ends of said frame, a pair of opposed rotary cutters respectively carried by said cutter shafts, cutter housings pivoted on said rock shaft and having bifurcated upper ends for respectively supporting said cutter shafts at opposite ends of said cutters, and driving means at each end of said frame each including gears mounted on the projecting ends of said rock shaft means and said cutter shafts for rotating said cutters, and means for independently adjusting said cutters and the associated driving means therefor arcuately about said rock shaft to vary the position of said cutters relative to each other.
4. A machine for milling round metal bar stock at high speeds comprising a cutter shaft, a cutter on said shaft intermediate the ends thereof, a rock shaft, a cutter support pivoted on said rock shaft and having a bifurcated upper end, bearing means on said upper end for supporting said cutter shaft at opposite ends of said cutter, means including gears respectively mounted on said cutter shaft and on said rock shaft for rotating said cutter, a stationary gear housing enclosing said gear on said rock shaft, and an adjustable gear housing enclosing said gear on said cutter shaft, said gear housings having arcuate meeting edges formed on a radius about said rock shaft to permit arcuate adjustment of the cutter about the rock shaft.
